United States Patent Office

Des. 219,983
Patented Feb. 23, 1971

219,983

HEARING AID

Juan Gasso Bosch, Via Layetana 158, and Jorge Borguño
Clua, Ronda Universidad 12, both of Barcelona, Spain

Filed Jan. 10, 1967, Ser. No. 5,370

Term of patent 7 years

Int. Cl. D14—04, 99

U.S. Cl. D26—14

FIG. 1

FIG. 2

FIG. 3

FIG. 4

FIG. 1 is a front perspective view of a hearing aid showing my new design;

FIG. 2 is a rear perspective view thereof;

FIG. 3 is a front perspective view of a modified embodiment of the hearing aid shown in FIG. 1; and

FIG. 4 is a rear perspective view thereof.

We claim:

The ornamental design for a hearing aid, as shown and described.
